CONTAINER FOR BARBERS' CLIPPERS AND VIBRATORS

Alfred L. McDowell, San Jose, Calif.

Application July 17, 1948, Serial No. 147,642

Term of patent 3½ years

(Cl. D80—11)

To all whom it may concern:

Be it known that I, Alfred L. McDowell, a citizen of the United States of America, residing at San Jose, in the county of San Francisco and State of California, have invented a new, original, and ornamental Design for a Container for Barbers' Clippers and Vibrators, of which the following is a specification, reference being had to the accompanying drawing, forming a part thereof.

The figure is a perspective view of a container for barbers' clippers and vibrators, showing my new design.

The dominant features of my design reside in the portions shown in full lines.

I claim:

The ornamental design for a container for barbers' clippers and vibrators, substantially as shown and described.

ALFRED L. McDOWELL.
